EQUIPMENT FOR TESTING SHIELDS

Guy D. Johnson, Jr., and Kenneth J. Matzinger,
Detroit, Mich.

Application October 23, 1944, Serial No. 560,070

5 Claims. (Cl. 175—183)

(Granted under the act of March 3, 1883, as
amended April 30, 1928; 370 O. G. 757)

The invention described herein may be manufactured and used by or for the Government for governmental purposes, without the payment to us of any royalty thereon.

The invention to be hereinafter described relates to equipment for testing resistor suppressors or other series impedance elements with respect to various shields, for radio noise suppression and filtering purposes, where both ends of the series element are above ground potential for the currents to be filtered or suppressed.

Heretofore there has been no known equipment for readily and inexpensively determining with appreciable certainty the most practical diameter of shield for a given noise suppressor or filter element in an electric circuit.

The main objects of the present invention are to provide a simple, efficient compact equipment whereby such determinations may be definitely made in the shortest time, with the least difficulty and in relation to a very wide range of high frequency noises or currents created by or resulting from as many different sources.

In order to disclose more clearly the construction, operation and use of the invention, reference should be had to the accompanying drawing forming part of the present application. Throughout the several figures of the drawing like reference characters designate the same parts in the different views.

In the drawing—

Fig. 1 is a diagrammatic view showing one application of the invention; and

Fig. 2 is a longitudinal cross section through the test unit of the invention.

Referring to the drawing in detail, and particularly to the test unit shown in Fig. 2, 1 indicates a suitable cylindrical tube of brass or equivalent material for mounting or supporting the unit in operative position in a circuit such as shown in diagram in Fig. 1 of the drawing. The inside diameter of this tube is determined by the greatest inside diameter of the shield which it is desired to test for a particular resistor.

The unit to be mounted in and supported by tube 1 is shown in detail in the longitudinal cross sectional view of Fig. 2. Referring to the drawing in detail and more particularly to Fig. 2, insulating end cylinders 2 of polystyrene or substantially equivalent material are used, one at each end of cylinder 1. They are identical and, therefore, only one will be described in detail as its description is, equally, that of the other. One end of each cylinder is longitudinally bored as at 3 to provide a chamber concentric with 1 for 55

adequately receiving a tubular cable end connector 4 of well known construction. The opposite end of each end cylinder 2 is similarly bored as at 5 concentrically with the longitudinal axis of 2 but to a considerably less diameter, leaving between bores 3 and 5 a partition. This partition is perforated or pierced, concentrically with bores 3 and 5, for free passage for a headed contact screw 6. Screw 6 is turned into a threaded opening in the end of 4 to draw 4 into solid and positive seating against the inner end of its bore 3. The under face of the contact screw 6 and the cooperating face of the partition may be suitably beveled to provide better and firmer seating, as will be readily understood.

Within and closely fitting bore 5, extends one end of the tube or cylinder 7 of suitable insulating material. Within cylinder 7 are disposed the two short cylindrical rods 8 of polystyrene or substantially equivalent material with the resistor-suppressor element 9 between them and also within the tube 7. Extending loosely centrally through a small diameter bore of each rod 8 is a suitable conductor 10 one end of which is carried appreciably beyond the rod end and coiled to provide a compression spring 11 insuring good contact with the respective contact screw 6 and to maintain all parts closely assembled. The opposite end of each wire is overturned, radially, against the face of its rod end to provide efficient contact with the adjacent end of the resistor-suppressor element 9.

Concentric with the insulator cylinder 7 may be disposed a spacing sleeve 12 of polystyrene or substantially equivalent material. Sleeve 12 has an internal diameter substantially equal to the external diameter of the cylinder 7. Over sleeve 12 is removably mounted an electrostatic tubular shield 13 having the same internal diameter as the external diameter of sleeve 12. This shield 13, preferably, is of brass or substantially equivalent material. A second electrostatic shield 14 is mounted over the brass shield 13. Its internal diameter should be approximately equal to the external diameter of shield 13 and its external diameter should be equal to the internal diameter of cylinder 1 or the external diameter of the short end of cylinder 2. While two brass cylinders 13 and 14 have been specifically referred to, one may be used having the total measurements of the corresponding combined measurements of the two.

This unit of the invention may be assembled in the following manner: After connecting the respective cable ends to connectors 4 in usual

manner, secure the connectors in their respective bores 3 and make them fast by screws 6. Now slide one cylinder 2 into the supporting brass cylinder 1 and partially close the adjacent end of cylinder 1 by the threaded flanged collar 15 and cooperating annular plate 16 which will, in assembled relation, overlap the end of the cylinder 2. Slip one end of 7 into the corresponding bore 5 of 2. Then, in proper order, insert the rods 8 and resistor-suppressor element 9. Next, in proper order, slip over 7 the polystyrene spacing sleeve 12 and the brass shields 13 and 14. Now, insert the remaining end cylinder 2 of polystyrene and apply the remaining flanged threaded collar and annular plate 15 and 16. The parts are so proportioned, of course, that turning of the second collar 15 to clamping position forces the parts together so that there is good efficient contact between 6 and 11 and between element 9 and the ends of wire 10.

As shown in the drawings, shields 13 and 14 are coupled by set screws 11. Obviously, where a single shield of the desired diameter is used such fastenings will be eliminated.

When this unit has been completely assembled, as above, a set screw 18 may be turned through 1 and into 14 to assist in retaining the parts in assembled relation.

It will be seen that shields of any diameter ranging from the smallest permissible with satisfaction of required insulation for the resistor-suppressor shown, to the largest receivable by cylinder 1, may be used in the device illustrated. That gives a considerable range of diameters of shields for testing. With larger diameters of cylinders 1 a greater range of diameters of shields may be used. This range of diameters for testing will vary with varying circumstances and conditions, all of which are well understood by those skilled in the art to which this invention relates.

Radio frequency noise suppressors such as the resistor-suppressor 9 above described are of widespread use. They act as obstructions or dams in a circuit, reducing to a greater or less degree, the flow of interfering radio frequency currents along the conductor. Because of capacitive coupling between the terminals and leads at opposite ends of the suppressor, and fringing capacitances, shunting the suppressor, these currents will be bypassed around the resistor or suppressor to a degree depending on the frequency, and on the capacitances and the resistance of the suppressor. In such cases the particular resistor-suppressor is inefficient to that extent.

To prevent or minimize such bridging actions, tubular electrostatic shields are used about the resistor-suppressor elements. The effectiveness of the shields at frequencies making the impedance of the shunt capacitance of the suppressors not high compared with the suppressor resistance depends greatly upon their inside diameter, and radial space between their inner walls and the enclosed resistor-suppressor element. By reducing the radial space as far as practicable, the electrostatic lines of force which would otherwise bypass the resistor-suppressor, are intercepted by the shield and grounded.

The most effective electrostatic shield for resistor-suppressors in high tension ignition systems of gasoline engines at high frequencies, for instance, is the one having the least inside diameter relative to the enclosed resistor-suppressor, compatible with proper insulation between shield and resistor-suppressor, provided that corona, which can itself become a source of radio noise

interference, does not occur. Corona may occur in air spaces around the suppressor if the shield fits too closely around the suppressor, due to the resulting high potential gradients in the air. If the corona cannot be prevented, by proper shaping of parts and by filling up all air spaces subject to excessive potential gradients with a suitable insulating material, the optimum diameter of shield will be the smallest that will not cause corona, rather than the smallest that will not cause dielectric breakdown.

The present invention is designed to permit evaluation of the relative shielding benefits to be obtained by various relative diameters of shield and suppressor, and various lengths and length-to-diameter ratios of the suppressor, at various radio frequencies, without having the measurement of the interference leakage through and around the suppressor obscured by interference emanating from other parts of the ignition system.

In order to use the unit hereinabove described, a noise source compartment 21 and test compartment 26 are provided, arranged close together and adapted to be suitably mounted on a bench or table. They may be so spaced that the opposite ends of a cylinder 1 may be supported in and by the adjacent walls of the respective chambers. Within chamber 21 is the noise generating means such as the ignition impulse generator 22 grounded through 25. Within test compartment 26 is the noise radiating loop 27. Mounted in the adjacent walls of 21 and 26 are two units, 19 and 20, such as that hereinbefore described in detail. One is connected to spark gap 24 and to one end of 27. The other is connected to the generator 22 and to the other end of loop 27. This places units 19 and 20, loop 27, generator 22 and spark gap 24 in series. Within chamber 26, suitably supported on insulators 29 is an antenna 28 or noise pick-up means arranged about the loop 27 in spaced relation and approximately in the same plane with 27. This pick-up, by a suitable lead-in 30 passing through a tubular shield 31, is connected to a well known type of radio receiver and output meter 32, used as a frequency-selective power or voltage measuring device. Preferably, a radio frequency attenuator (not shown), is used as a part of the input circuit of 32. If the attenuator is calibrated, the difference in attenuator settings to give equal output from the receiver with different sets of shields and suppressors inserted in 19 and 20, will be a direct measure of the relative effectiveness of the different shields and suppressors. The output meter of 32, clearly indicates by scale reading, in proportion to the current passing over loop 27. At the same time the corresponding sound may be heard by radio if desired. So, if it is desired to determine whether a given shield may be improved upon, that shield will be placed in the units 19 and 20 and the interference current passed will be noted. Then, successively, other shields of varying inside diameter will be similarly placed in 19 and 20 and comparative readings taken. Of course the same diameter shield will be placed in both 19 and 20 for the respective reading or test. The sounds corresponding to the respective current readings may, of course, also be observed and noted.

Anyone skilled in the art could adapt this system to testing the effectiveness of such shields in improving the efficiency of radio-frequency chokes or other series impedance elements in circuits in which both ends of the element are above ground potential. The particular embodiment

ment described in this specification is designed to simulate substantially the conditions occurring in a typical automotive ignition system. Since the various impedances in the circuit will determine the effectiveness of a particular shield at a particular frequency, it would be desirable to arrange the source of radio frequency current (e. g. ignition system or electron tube generator) and the load to simulate the conditions to be encountered in the actual application. If the series element is a choke coil, the effect of the shield on the resonant frequency of the coil with its effective distributed capacitance may be important, thus determining an optimum shield diameter greater than the minimum possible, as would be desirable in the case of a resistive series element where corona and insulation are not limiting factors.

It is thought that the construction, operation and use of the invention will be clear from the preceding detailed description.

Changes may be made in the construction, arrangement and disposition of the various parts of the invention within the scope of the appended claims without departing from the field of the invention and it is meant to include all such within this application wherein only one preferred form has been disclosed by way of illustration and with no thought or intent to, in any degree, limit the invention thereby.

Having thus described our invention, what we claim and desire to protect by Letters Patent is:

1. Testing equipment of the character described comprising a shielded chamber containing a source of high frequency energy, a shielded high frequency pick-up chamber, an impedance element mounted within shielding between said chambers, an electric circuit extending within both said chambers and comprising means of electrically coupling the high frequency current passed by said impedance element to a means of indicating the value of said current.

2. Testing equipment of the character described comprising a shielded chamber containing a radio noise source, a radio noise pick-up chamber, an electric circuit extending within both said chambers and comprising a noise radiating loop in said pick-up chamber and suppressor elements

between said chambers and in series with said loop and the radio noise source in said noise chamber and means for indicating the radio frequency current passed by the suppressor elements.

5 3. Testing equipment of the character described comprising a shielded chamber containing a radio noise source, a radio noise pick-up chamber, an electric circuit extending within both said chambers and comprising a noise radiating loop in said pick-up chamber, shielded suppressor elements between said chambers and in series with said loop and the radio noise source in said noise chamber, means for changing the shields of said suppressors and means for indicating the respective radio frequency currents passed by the suppressors under various shield conditions.

4. Testing equipment of the character described comprising a shielded chamber containing a radio noise source, a radio noise pick-up chamber, an electric circuit extending within both said chambers and comprising a noise radiating loop in said pick-up chamber and suppressor elements between said chambers and in series with said loop and the radio noise source in said noise chamber, an antenna within said pick-up chamber disposed to pick up noise radiated by said loop and means associated with said antenna for indicating the radio frequency currents passed by said suppressors.

30 5. Testing equipment of the character described comprising a shielded chamber containing a radio noise source, a radio noise pick-up chamber, an electric circuit extending within both said chambers and comprising a noise radiating loop in said pick-up chamber and shielded suppressor elements between said chambers and in series with said loop and the radio noise source in said noise chamber, means for varying the shields of said suppressor elements, an antenna within said pick-up chamber disposed to pick up noise radiated by said loop, and means associated with said antenna for indicating the respective radio frequency currents passed by the suppressors under various shield conditions.
